UNITED STATES PATENT OFFICE.

ABRAHAM NOVICK, OF BROOKLYN, NEW YORK, ASSIGNOR TO F. L. SMITH'S MACHINE COMPANY, INCORPORATED, OF NEW YORK, N. Y., A CORPORATION OF NEW YORK.

MACHINE FOR MAKING LINED ENVELOPES.

1,421,816.

Specification of Letters Patent. Patented July 4, 1922.

Application filed October 7, 1920. Serial No. 415,225.

To all whom it may concern:

Be it known that I, ABRAHAM Novick, a citizen of the United States, and a resident of New York, borough of Brooklyn, in the county of Kings and State of New York, have invented certain new and useful Improvements in Machines for Making Lined Envelopes, of which the following is a specification.

10 This invention relates to envelope machines and particularly to that class thereof which is adapted for assembling and folding together an envelope blank and a lining therefor. The object of my improvements is to 15 provide a machine of the class specified which is simple in construction and speedy and accurate in operation. To these ends my improvements comprise features which are illustrated in their preferred embodiment 20 in the drawings accompanying this specification, wherein:—

Figure 1 is a side elevation of so much of an envelope machine as is needed to suitably show my improvements, the view being taken 25 looking in the direction of arrow 1 of Fig. 3. Fig. 2 is a front elevation looking in the direction of arrow 2 of Figs. 1 and 3. Fig. 3 is a plan view corresponding with the elevations of Figs. 1 and 2, those parts above line 30 A—A of Fig. 1 being broken away to more clearly show the mechanism below. All the figures of the drawings are to one scale.

The envelope blanks E are supported in a pile on an elevating device comprising a vertical slide 3 having rack 4 engaged by gear 5 fixed to shaft 6. Said shaft has also fixed thereto worm gear 7 which is driven by worm 8 fixed to shaft 9 turning in bearing 10. To the left hand end of said shaft 9 is 40 fixed ratchet 11 and which ratchet is intermittently rotated by a pawl not shown. For governing the operation of said pawl, to elevate from time to time the pile of blanks E, an oscillating finger 12 pivoted at 13 in up- 45 standing bracket 14 is provided.

The operation of said finger 12 will be more clearly understood in connection with the description herein of the construction and operation of the elevating and governing mechanism for the lining blanks L, which mechanism is more fully shown and is of the same general character as that provided for the envelope blanks. It will also be understood that both of said mechanisms are similar to the showing of United States Patent

1,063,140 issued to Ferdinand L. Schmidt, May 27, 1913.

Referring now to the elevating mechanism for said lining blanks L, vertical slide 15 has rack 16 thereof in engagement with pinion 60 17 fixed to the right hand end of shaft 18, Fig. 1. The left hand end of said shaft is provided with hand-wheel 19 for hand manipulation. Between gear 17 and hand-wheel 19 ratchet 20 is fixed to shaft 18. Oscillating 65 arm 21 loosely mounted on said shaft carries pawl 22, and detent pawl 23 is pivotally mounted to a fixed part of the structure 111. Pivoted for oscillation in ear 24 of arm 21 is arm 25, one end of which carries pin 26 for 70 engagement with one end of arm 21 and the other end 25^a of which is adapted to engage pin 27 of said arm 21. Oscillating movement is imparted to arm 25 from cam 28 on shaft 29 through roll 32 on arm 84 fixed to rock 75 shaft 31, and thence through arm 30 fixed to that same rock shaft, through link 33 to rock arm 34, fixed to shaft 35. Also fixed to said shaft is arm 36 connected by link 37 to end 25^a of arm 25. Also fixed to shaft 35 is feeler 80 finger 38 for intermittent engagement with the top of the pile of blanks L. The amount of oscillation of the several arms 30, 34, 25 and 21 is governed by the height of said pile of blanks. When the top of said pile is sufficiently lowered by the successive removal of the blanks, arm 21 is oscillated a sufficient 85 distance to cause pawl 22 to engage the next successive tooth on ratchet 20, whereby the pile of blanks is slightly elevated. When it 90 is desired to lower slide 15 to replenish the stock of blanks L eccentric lever 39 is turned downwardly, Fig. 2, to free pawls 22, 23 from engagement with ratchet 20, thereby permitting slide 15 to descend. Cam shaft 95 29 may be driven by means of sprocket 107 fixed thereon and chain 108, from a shaft below not shown.

The envelope blanks from pile E are removed one at a time from the top of said 100 pile by the usual vertically reciprocating pickers 41, 41, and said pickers are caused to adhere to and deposit gum on the uppermost blank by the application of gum to their lower faces by means of reciprocating gum 105 roll 42. Said gum roll, in its travel to the right, Fig. 2, engages roll 43 in gum box 44. Said roll 43 is rotated by means of suitable gearing from pulley 45 driven by belt 46 from some convenient source of power on 110

the machine. Said pickers 41, 41 are reciprocated vertically by lever 47 from a suitable cam on shaft 29 not shown. Gum roll 42 is mounted for free rotation in carriage 48 5 slidably mounted on rods 49, 49. Said carriage is caused to traverse said rods by means of levers 50, 50 connected thereto by links 51, 51. Levers 50, 50 are fixed to shaft 52 and one of said levers has outstanding arm 10 53 which, by means of rod 54, is oscillated from a suitable cam not shown.

After gummed pickers 41, 41 lift the top blank of the pile to a position just below stripping plate 55, Fig. 2, a reciprocating 15 carrier comprising slides 56, 56, having hooked ends as 57, reciprocates horizontally to below that top blank. The pickers then ascend a sufficient distance further to cause the stripping plate to strip the blank from 20 said pickers, and which blank then falls onto said slides and is carried forward thereby from its initial position to position E¹, Fig. 3, ready to receive the lining blank.

To insure the passage of the bottom flap 25 of the envelope blank onto table 90 without catching, bridge 91 having a downwardly inclined receiving edge 92 is provided. Said bridge is mounted to swing horizontally on pivot 93 and is actuated at suitable times 30 from within pocket 95 in table 90 through rod 94 from a cam not shown. To hold the traveling envelope blank down onto slides 56, 56, overhead rails 101, 101 are provided. For causing the envelope blank to be properly located at the lining blank receiving 35 station, position E¹, stop fingers 64, 64 are provided. Said fingers are fixed to shaft 65 which is rocked at suitable times through rod 66 from a cam, not shown, on shaft 29. 40 To prevent the envelope blank from retracting from position E¹, detent fingers 102, 102 are provided.

It will be observed that that picker 41 which gums the bottom flap of the envelope 45 blank, is provided with inreaching opposite ears 41^a, whereby two inwardly reaching patches of gum are provided onto which to seat the opposite bottom corners of the lining blank. Also if desired the gum on the 50 seal flap of the envelope blank may extend inwardly sufficiently to underlay the V shaped end of the lining blank.

Slides 56, 56 are actuated from a suitable cam, not shown, through rod 58 pivotally 55 connected at 59 to arm 60 fixed to rock shaft 61. Also fixed to said shaft are upstanding arms 62, 62 connected by links 63, 63 to said slides respectively.

For delivering the lining blanks one at a 60 time into position over and onto the successive envelope blanks at position E¹, said lining blanks are picked up from their pile L, at one side of the path of travel of the envelope blanks, and moved transversely to 65 the direction of travel of the envelope blank.

For this purpose pneumatic means are preferably employed. Said means comprise carriage 67 mounted for horizontal travel to left and right, Fig. 2, on rail 68. Said rail is fixed at either end to vertical slides 70 69, 69, whereby carriage 67 may be raised and lowered to cause pneumatic pickers 70, 70 to descend onto the top of the pile of lining blanks and to rise therefrom with the topmost blank. 75

Said carriage 67 is caused to traverse horizontally on rail 68 by means of lever 71, fixed to rock shaft 72, and which lever is connected to said carriage by link 73. Also fixed to rock shaft 72 is arm 74 carrying roll 75 for engagement with cam 76 fixed to shaft 29, for rocking arm 71. For causing slides 69, 69 and rail 68 to reciprocate vertically, rock arms 77, 77 fixed to rock shaft 78 are connected by links 79, 79 85 and ears 80, 80, to said rail 68, and said shaft 78 is rocked at suitable times from cam 81 through roll 82 on arm 83 fixed to said shaft.

For exhausting the air from suction pickers 90 70, at suitable times, pump 85 is provided. Said pump may be operated through piston rod 86 from some suitable source of power, not shown. For admitting air to said pump and to thereby cut off the suction from 95 the pickers valve 96 is provided. Said valve may be operated at suitable times by cam 97 acting against valve lever 98. Said cam is rotated from some convenient means, not shown. Flexible pipe 87 leads from the upper end of pump 85 to the head of carriage 67, from where flexible pipes 88, 88 lead to the several pneumatic pickers 70, respectively. Those pickers 70 which lift the pointed end of the lining blank are prefer- 100 ably each provided with a presser-foot 89, for pressing that pointed end onto the envelope blank, when delivered thereover. When carriage 67 is moved to the right 110 from its position of Fig. 2 to a position over the pile of lining blanks, rail 68 is lowered to cause the pickers to contact with the top lining blank of the pile. The air is then exhausted from the pickers and those pickers rise, thereby lifting the top blank. Carriage 67 then moves to the left, Fig. 2, and the pickers descend and deliver the lining blank 115 in position on the envelope blank as shown in dotted lines in Fig. 3, with those corners of the lining blank adjacent the bottom flap of the envelope in contact with the inreaching gummed portions deposited by gummer ears 41^a, 41^a, and presser feet 89, 89 press the other end of the lining blank down onto the envelope blank. Pump valve 96 is then 120 opened, thereby admitting air to the pneumatic system and neutralizing the suction in said pickers. Those pickers then ascend, leaving the lining blank in possession of the envelope blank.

The assembled blanks are now ready to be transported to position E² over folding box 99. This is accomplished by a second set of hooks 100, 100 on slides 56, 56 respectively. As said slides reciprocate to the right in Fig. 1, stop fingers 64, 64 are depressed to permit the assembled blanks to proceed on their journey to the folding box. Also, to assist the leading end of the assembled blanks to pass over the farther edge of the folding box without catching, fingers 109, Fig. 3, having downwardly inclined leading ends, Fig. 1, are projected partially across the folding box. These fingers are carried and operated by lever 110, which is in turn actuated from a cam, not shown, on shaft 29. When said assembled blanks are delivered over said folding box 99 they encounter hooks 103, 103, whereby they are properly located relatively to their direction of travel. Fingers 109 then retract from over the folding box and plunger 104 descends, pushing the assembled blanks into the folding box, whereby the several flaps of the blanks are folded up. The continued downward movement of said plunger delivers the blanks to folding bed 105 where the usual folding wings, as 106, fold the several flaps, as well known in the art. Plunger 104 and folding wings, as 106, are actuated in proper time by means not shown but of well known character.

I claim:

1. In an envelope machine for making lined envelopes, the combination of a support for a pile of envelope blanks, a lining blank receiving station, means for moving an envelope blank from said support to said lining receiving station, another support for a pile of lining blanks, and means for moving a lining blank in a rectangular path from said other support onto said envelope blank at the receiving station.

2. In an envelope machine for making lined envelopes, the combination of a support for a pile of envelope blanks, a lining blank receiving station, means for moving an envelope blank from said support to said lining receiving station, another support for a pile of lining blanks, means for moving a lining blank in a rectangular path from said other support onto said envelope blank at the receiving station, a folding box, means for moving the assembled two blanks to said folding box, and means for folding the assembled two blanks into an envelope.

3. In an envelope machine for making lined envelopes, the combination of a support for a pile of envelope blanks, a lining receiving station, means for moving an envelope blank from said support to said lining receiving station, another support for a pile of lining blanks at one side of the path of travel of the envelope blanks, and means for moving a lining blank in a rectangular

path from said other support onto said envelope blank at the lining receiving station.

4. In an envelope machine for making lined envelopes, the combination of a support for a pile of envelope blanks, a lining receiving station, means for moving an envelope blank from said support to said lining receiving station, another support for a pile of lining blanks at one side of the path of travel of the envelope blanks, means for moving a lining blank in a rectangular path from said other support onto said envelope blank at the lining receiving station, a folding box, means for moving the assembled two blanks to said folding box, and means for folding the assembled two blanks into an envelope.

5. In an envelope machine for making lined envelopes, the combination of a support for a pile of envelope blanks, a lining receiving station, means for moving an envelope blank from said support to said lining receiving station, another support for a pile of lining blanks, and means for moving a lining blank in a rectangular path from said other support in a direction transverse to the direction of movement of the envelope blank and for delivering said lining blank onto said envelope blank at the lining receiving station.

6. In an envelope machine for making lined envelopes, the combination of a support for a pile of envelope blanks, a lining receiving station, means for moving an envelope blank from said support to said lining receiving station, another support for a pile of lining blanks, means for moving a lining blank in a rectangular path from said other support onto said envelope blank at the lining receiving station, a folding box, a reciprocating carrier having means thereon for advancing an envelope blank from its initial position to the lining receiving station, said carrier having other means thereon for advancing the assembled two blanks from the lining receiving station to the folding box, and means for removing an envelope blank from said first support and for delivering said blank to said carrier.

7. In an envelope machine for making lined envelopes, the combination of a support for a pile of envelope blanks, a lining receiving station, means for moving an envelope blank from said support to said lining receiving station, another support for a pile of lining blanks at one side of the path of travel of the envelope blanks, means for moving a lining blank in a rectangular path from said other support in a direction transverse to the direction of movement of the envelope blank and onto said envelope blank at the lining receiving station, a folding box, a reciprocating carrier having means thereon for advancing an envelope blank from its initial position to the lining receiving sta-

tion, said carrier having other means thereon for advancing the assembled two blanks from the lining receiving station to the folding box, and means for removing an envelope blank from said first support and delivering said blank to said carrier.

8. In an envelope machine for making lined envelopes, the combination of a support for a pile of envelope blanks, a lining receiving station, means for moving an envelope blank from said support to said lining receiving station, another support for a pile of lining blanks, means for moving a lining blank in a rectangular path from said other support onto said envelope blank at the lining receiving station, a folding box, a reciprocating carrier having means thereon for advancing an envelope blank from its initial position to the lining receiving station, said carrier having other means thereon for simultaneously advancing two assembled blanks from the lining receiving station to the folding box, and means for removing an envelope blank from said first support and delivering said blank to said carrier.

9. In an envelope machine for making lined envelopes, the combination of a support for a pile of envelope blanks, a lining receiving station, means for moving an envelope blank from said support to said lining receiving station, another support for a pile of lining blanks, and means for moving a lining blank from said other support and for delivering said lining blank onto said envelope blank at the lining receiving station comprising a lining blank picker carriage, a lining blank picker on said carriage, a rail on which said carriage is slidably mounted, means for reciprocating said carriage on said rail, and means for lowering and raising said rail.

10. In an envelope machine for making lined envelopes, the combination of a support for a pile of envelope blanks, a lining receiving station, means for moving an envelope blank from said support to said lining receiving station, another support for a pile of lining blanks, means for moving a lining blank from said other support and for delivering said lining blank onto said envelope blank at the lining receiving station comprising a lining blank picker carriage, a lining blank picker on said carriage, and a rail on which said carriage is slidably mounted, means for reciprocating said carriage on said rail, means for lowering and raising said rail, a folding box, means for moving the assembled two blanks to said folding box, and means for folding the assembled two blanks into an envelope.

11. In an envelope machine for making lined envelopes, the combination of a support for a pile of envelope blanks, a lining receiving station, means for moving an envelope blank from said support to said lining receiving station, another support for a pile of lining blanks at one side of the path of travel of the envelope blanks, and means for moving a lining blank from said other support in a direction transverse to the direction of movement of the envelope blank and for delivering said lining blank onto said envelope blank at the lining receiving station comprising a lining blank picker carriage, a lining blank picker on said carriage, a rail on which said carriage is slidably mounted, means for reciprocating said carriage on said rail, and means for lowering and raising said rail.

In witness whereof, I hereby affix my signature this 4th day of October, 1920.

ABRAHAM NOVICK.
